DAVID L. LINDQUIST, OF YONKERS, NEW YORK, ASSIGNOR TO OTIS ELEVATOR COMPANY, OF JERSEY CITY, NEW JERSEY, A CORPORATION OF NEW JERSEY.

SAFETY DEVICE.

1,300,424.

Specification of Letters Patent. Patented Apr. 15, 1919.

Application filed March 16, 1916. Serial No. 84,589.

To all whom it may concern:

Be it known that I, DAVID L. LINDQUIST, a subject of the King of Sweden, residing in Yonkers, in the county of Westchester and State of New York, have invented a new and useful Improvement in Safety Devices, of which the following is a specification.

My invention relates to an improvement in elevator safety devices, and provides a safety 10 which will exert a practically constant retarding action on the car, regardless of variation of friction between the safety clamping jaws and the guide rails.

In the present day safety device, the rail 15 is gripped with a predetermined force and the braking effort exerted thereby on the elevator car will depend on the intensity with which the rail is gripped and the coefficient of friction between the gripping means 20 and the rail. The latter is a quantity depending on many circumstances, as for instance, on the surface of the rail whether rough or smooth, on the consistency and nature of the rail lubricant, on the material of 25 the rail and gripping means, whether soft or hard, or whether crystalline or fibrous in structure. It is clear therefore that the intensity of the grip must be designed to bring car and load to rest with the least coefficient 30 of friction.

In actual practice the frictional retarding force varies considerably and this is mostly due to rough or soft spots in the rail or lack of lubrication. Lack of lubrication, for instance, frequently leads to seizure of the rail 35 with the result that the car comes to rest with a hard jolt dangerous to life and limb of the passengers. Moreover, the coefficient of friction is never the same at each of the 40 two rails which guide the car, so that the braking force exerted on one side of the car is always larger than on the other side, and frequently to such an extent that the car frame is bent out of shape.

The object of my invention is to obviate 45 these defects and disadvantages and to so arrange the gripping means that the retarding force exerted on the car will be independent of variations in the coefficient of 50 friction. In other words, the safety device as hereinafter described is so arranged that it will automatically adjust itself to exert a constant braking force irrespective of the conditions of the surface of the rail, its hardness or lubrication.

Figure 1 is a part sectional view of a safety plank carrying my device; Fig. 2 is a sectional view showing in detail my improved guide rail clamping means in inoperative position; Fig. 3 is similar to Fig. 2, but 60 shows the safety in operated position; Fig. 4 shows an elevator system wherein my device is used.

Referring to the drawings in detail, a drum, D, is carried by a safety plank, P, the 65 plank being carried by the elevator car. The drum, which is mounted for rotation by a cable, 1, attached to a governor rope, 2, is bored to receive a sleeve member, S, the latter having a screw threaded bore to receive 70 a screw threaded rod, 3. The end of the rod, 3, opposite to that entering the bore of the sleeve, S, is also screw threaded and enters a screw threaded bore in a gear 4. This gear forms part of a manual means for operating 75 the safety, and also a coupling to couple together the rod 3 and another screw threaded rod 5, this rod being threaded oppositely to the rod, 3. With this structure, when the drum, D, is rotated, the rod 5 will be moved 80 bodily longitudinally. On the end of the rod, 5, opposite to the screw threads, is mounted a wedge member adapted to engage 85 rollers on the ends of levers 7 and 8, and as these levers are pivoted at 11, a longitudinal movement of the rod 5 to the left will force the wedge member between the rollers and cause the ends of the levers to separate. This forces the clamping members 9 and 10 on the other end of the levers toward the guide rails 90 to grip the same. This description is that of the left hand half of the safety plank. The other half of the safety is the same, the rods 3' and 5' in this instance being threaded oppositely to the rods 3 and 5 just described, 95 in order that they will travel oppositely to the travel of the rods 3 and 5.

To actuate the drum, D, and thereby operate the safety, I have shown two means, illustrated in Fig. 4. One is automatic, the 100 governor rope 2 being clamped between clamping members, 32, when the car overspeeds. This clamp action will stop the rope 2 and the further travel of the car will exert a pull on the drum through the cable, 1, 105 which as before pointed out is attached both to the drum and the governor rope. The other means for operating the safety is manual, in its operation, comprising a hand wheel 28 in the car, suitably geared to a 110

sprocket 29 on the plank, P, this sprocket carrying a gear meshing with a rack 30, which in turn engages a gear 31 connected to the drum, D. In both cases, therefore, the 5 drum, D, will be rotated to cause the safety to operate.

Referring now to Figs. 2 and 3. Interposed between the outer ends of the members 7 and 8 and the guide rail, 18, are 10 wedges, 9 and 10, to engage the rail when the safety is operated, the faces of the members 7 and 8 toward the wedge members being inclined to correspond to the inclination of the inclined faces of the wedge members. 15 Interposed between the wedges and the members 7 and 8, are rollers 14, 15, 16 and 17, these rollers normally resting on pins 18, 19, 20 and 21, provided for that purpose in the members 7 and 8. The lower ends of 20 the wedge members are turned down to receive heavy coil springs, 24 and 25, which are retained in place by nuts 26 and 27 screwed on the lower end of the turned down portions, 22 and 23, the upper ends of these 25 springs bearing against the bottom of the members 7 and 8.

For best results I find that it is preferable to have the angle of inclination of the faces of the wedge members small, and the springs 30 24 and 25 correspondingly long.

The operation of the safety is as follows: The forces actuating the clamping members 7 and 8 are transmitted through the rollers 14, 15, 16 and 17 onto the inclined surfaces 35 of the wedges 9 and 10, the latter grip the rail and in turn will give rise to frictional forces which tend to cause the wedges to move upwardly relative to the clamping means and against the action of their respective springs 24 and 25. When the 40 flanges 12 of the wedges 6 engage with the rollers at the end of levers 7 and 8, the inward movement of the members 7 and 8 ceases and the latter remain stationary. At 45 this instant the springs 24 and 25 have suffered a certain compression corresponding to the upward motion of the wedges 9 and 10, as shown in Fig. 3, and the braking force exerted on the car will depend on the spring 50 compression and the coefficient of friction at the contact between wedges 9 and 10 and the rail. At any increase in the friction, say a rough spot on the rail, the wedges 9 and 10 tend to move upwardly, but since the clamping members 7 and 8 stay stationary, any 55 upward movement would at once release the frictional engagement between the wedges 9 and 10 and the rail. Upon the release of the frictional engagement however, the 60 wedges 9 and 10, under the influence of the springs 24 and 25, will immediately be returned into full contact with the rail. This play of alternate release and reestablishment of the frictional engagement between 65 the wedge members 9 and 10 and the rail

will continue until the safety rides off the rough spot. The result of this action is to maintain the retarding action on the car practically constant, and not to increase it as would be the case with the types of safety now in the art. 70

The springs 24 and 25 are preferably of a great number of turns. Owing to the fact that the clamping members 7 and 8, the wedges 9 and 10, and the rail have a certain 75 elasticity, a slight upward motion of the wedges from their position in Fig. 3 would not release the frictional engagement. With a short spring, however, a slight upward movement of the wedges would cause a material increase in the spring tension, and consequently in the retarding force exerted on the car, and so as to maintain as nearly as possible a constant retarding force, long springs should be employed. A long spring 80 will in turn require a large upward movement of the wedges so as to create a sufficiently large spring compression when the wedges move from their inoperative position in Fig. 2 to the operative position of 85 Fig. 3.

The advantage of a small wedge angle will now be appreciated, since for a given inward movement of the clamping members 7 and 8, the upward movement of the wedges 95 will be larger the smaller the wedge angle.

I desire not to be limited to the precise details and arrangements of parts herein shown, as others skilled in the art might make various changes therein without departing from the spirit and scope of my invention. 100

What I claim is:—

1. In a car brake or catch, a rail engaging member having an inclined face, means engaging said inclined face to actuate said rail engaging member, a spring between the rail engaging member and the actuating means, and means whereby the rail engaging member may be moved relatively to its actuating means against the action of said spring when the friction between it and the rail exceeds a predetermined amount, to maintain a practically constant retarding action on the car. 110

2. In a car brake or catch, the combination of a rail engaging member, a member for actuating said first named member, and so positioned relatively thereto that relative movement of the two members above a predetermined amount tends to release the frictional engagement of the rail engaging member with the rail, and a spring between the two members, tending to return the rail-engaging member into frictional engagement with the rail. 120

3. In a car brake or catch, the combination of a rail engaging member, a spring carried thereby, positively actuated means to actuate the rail engaging member, inclined 130

faces formed on the rail engaging member and the positively actuated means coöperating with each other and with the spring to maintain the friction of the rail engaging member on the rail practically constant.

4. In a car brake or catch, the combination of a wedge-shaped rail-engaging member, having its thick end uppermost, and means engaging the inclined face of said rail engaging member, the rail-engaging-member and the means engaging its inclined face having both a vertical and horizontal movement relatively to each other, and, a spring interposed between the rail-engaging member and the means engaging the inclined face of the said rail-engaging member, the parts coöperating to maintain a practically uniform retarding action on the car.

5. In a car brake or catch, the combination of a wedge-shaped rail-engaging member, having its thick end uppermost, and means engaging the inclined face of said rail-engaging member, the rail-engaging member and the means engaging its inclined face having a vertical movement relative to each other, said vertical movement causing a horizontal movement of one member relative to the other, a relatively upward movement of the rail-engaging member serving to decrease and a downward movement to increase the pressure on the rail inversely as the friction coefficient, and a spring between the rail engaging member and the means engaging its inclined face, the parts to maintain the retarding action on the car practically uniform.

6. In a car brake or catch, the combination of a wedge-shaped rail-engaging member, having its thick end uppermost, and means having a longitudinal movement relative thereto, and a spring between the rail-engaging member and the said means, the parts coöperating together to maintain a practically uniform retarding action on the car.

7. In a car brake or catch, the combination of a wedge-shaped rail-engaging member having its thick end uppermost, and means having a longitudinal movement relative thereto and coöperating with the inclined

face thereof, and a spring between the rail-engaging member and the said means, the parts coacting to maintain a practically constant retarding action on the car independent of variation in friction between the rail engaging member and the rail.

8. In a car brake or catch, the combination of a wedge-shaped rail-engaging member, having its thick end uppermost, means between which and the rail-engaging member there is relative movement, both vertical and horizontal, and a spring between the rail-engaging member and the said means, the parts coacting to maintain the retarding action on the car practically constant.

9. In a car brake or catch, the combination of a wedge-shaped rail-engaging member, having its thick end uppermost, means between which and the rail-engaging member there is relative movement, both vertical and horizontal, a spring interposed between the rail-engaging member and the said means, whereby the retarding action on the car will be maintained practically uniform.

10. In a car brake or catch, the combination of a wedge-shaped rail-engageable member, having a turned-down member extended from one of its ends, a nut on the said end, a wedge-shaped member for actuating the rail-engageable member, the faces that are opposite each other of the two members being inclined, rollers interposed between the inclined faces, pins on which the rollers normally rest, a coiled spring on the turned-down member, bearing between the nut and the actuating member.

11. In a car brake or catch, the combination of a rail-engaging member having an inclined face, a spring carried thereby, a second member having an inclined face, the spring and the inclined faces of the two members coöperating to maintain the retarding action on the car practically constant.

In testimony whereof, I have signed my name to this specification in the presence of two subscribing witnesses.

DAVID L. LINDQUIST.
